John Stewart,
ATTORNEY.

UNITED STATES PATENT OFFICE

GUSTAF F. BLIXT, OF GLEN ROCK, NEW JERSEY, ASSIGNOR OF ONE-HALF TO JOHN J. KRIESMER, OF HAWTHORNE, NEW JERSEY

MANUFACTURE OF PAPER CONTAINERS

Application filed June 15, 1929. Serial No. 371,107.

The underlying object of this invention is to provide the dairyman and other such users with a paper container which is inexpensive and which will come to him from the manufacturer with the assurance that its interior is uncontaminated by handling or any foreign bodies admitted since its manufacture and which he may then open and fill and then close, all by machine, if desired, and finally forward to the customer with the further assurance that the container will safely undergo in transit any reasonable amount of rough handling and that access to its contents once it is finally sealed cannot be had without the fact being apparent that the container has been tampered with.

In the drawing,

Fig. 1 is a side elevation of the finally sealed container;

Figs. 2, 3 and 4 are vertical sectional views showing the body and head at three different stages in the operation of forming the joint between them;

Figs. 5 and 6 are similar views showing the body and head at two different stages and illustrating a modification; and

Fig. 7 is a fragmentary sectional view of the material of which the parts may be composed.

The mentioned material may be paper coated or otherwise charged with paraffin wax, this being the material commonly used for forming containers where metal is not desired and jointing of the parts is present and stiffness and some plasticity are desirable or necessary.

1 designates the body, substantially tubular in form. Inward of its end 2 is an interior abutment surfaces 3, here tapering toward the opposite end of the body.

4 designates the head or closure. This is characterized by a pre-formed marginal roll 5 which is related as an overhang with respect to the exterior side of the central portion of the head.

To form the joint between these two parts the head is introduced into the end 2 and afterwards said end is bent over inwardly (as by a seaming operation acting progressively thereon around the axis of the body)

and against the roll, thus causing the latter to be compressed between said bentover end and the abutment surface 3. If the abutment surface is tapering, as in the example, the roll 5 will further be caused as an incident of the compression to move in wedging contact therewith, thereby resulting in effect a welding together of the parts, due to their plastic nature, such welding action augmenting the compression in insuring complete hermetic closing of the joint. To complete the resistiveness of the joint to disturbance, as by the pressure of the contents, the edge of the end 2 of the body is made to engage under the overhang formed by roll 5, as at 6.

Fig. 1 shows a container in which at each end of the body a joint 9 has been formed like the permanent joint above described and shown in section by Fig. 4.

In the best practice of the above stated method the head is forced against said abutment surface 3 and wedged thereinto previously to the end 2 acting to compress the roll 5 between itself and said surface, as in Fig. 3, so that it is definitely positioned and positively supported at the very outset of that operation. At this point in the procedure an article of manufacture, to wit, a container, is produced which in itself is useful as will be now pointed out:

Thus the manufacturer may assemble the container parts for shipment to the user so that one head (to form the bottom) would be permanently in place but the other head only wedged in, as in Fig. 3. The dairyman or other such user on receipt of the containers may then draw the latter heads, fill the containers and replace the heads and complete the joint in each case to the condition above described and shown by Fig. 4, all preferably by machinery. In the time between manufacture and receipt of the containers by the user, therefore, their interiors would be protected against handling and all other contamination; and the containers in the state now being referred to and shown by Fig. 3 would possess certain other advantageous features, to wit: they would be reinforced by the wedged-in state of their thus withdraw-

able heads and such heads would offer, under their overhangs, purchase to a suitable tool to effect the withdrawal.

In Figs. 5 and 6 a modification is illustrated in which, the portion of the body outward of the abutment surface 3 is itself tapered toward the opposite end of the body as at 2a, so that if the head 4 has a diameter greater than the least (or lowest) diameter of the inner surface of this taper there will occur 10 wedging and the mentioned welding independently of any such that may occur at said surface 3.

The method herein described and herein 15 after pointed out distinguishes from any previously proposed method of which I am aware in that the part 5 is pre-formed, whereby certain advantages result, herein pointed out and apparent to those skilled in the art, not resulting if said part is absent or if it is formed 20 contemporaneously with the bending over of the body end 2 or 2a.

Having thus fully described my invention what I claim is:

1. The method of closing the end of a tubular body of stiff sheet material having near 25 said end an interior abutment surface which consists in introducing into said end a head of stiff sheet material having a pre-formed 30 marginal roll and then bending said end over inwardly and against the head and thus causing the roll to be compressed between said bent-over end and abutment.

2. The method of closing the end of a tubular body of stiff sheet material having near 35 said end an interior abutment surface tapering toward the opposite end of the body which consists in introducing into said end a head of stiff sheet material having a pre-formed 40 marginal roll and then bending said end over inwardly and against the head and thus causing the roll to move in wedging contact with said surface.

3. The method of closing the end of a tubular body of stiff sheet material having near 45 said end an interior abutment surface which consists in introducing into said end a head of stiff sheet material having a pre-formed exterior overhang and then bending said end inwardly around the overhang and causing its 50 edge to engage under the same while supporting said head on said abutment surface.

4. A container formed of sheet material and including a tubular body and a head 55 wedged into one end of said body and having at its exterior side a marginal overhang under which a tool for withdrawing the head may be engaged.

60 5. A container formed of sheet material and including a tubular body and a head wedged into one end of said body and having its marginal portion curled inwardly and the edge thereof spaced from the outer surface 65 of the head and thereby forming an overhang

under which a tool for withdrawing the head may be engaged.

6. The method of closing the end of a tubular body of stiff sheet material having near 70 said end a circumferential inside taper converging toward the opposite end of the body which consists in introducing into the first end a head of stiff sheet material having its edge portion existing as a pre-formed marginal roll whose exterior surface forms a circumferential wedge-like surface on the head substantially conforming circumferentially 75 to the taper but exceeding in diameter the smaller diameter thereof, and applying pressure to the head to force the roll into said 80 taper.

In testimony whereof I affix my signature.
GUSTAF F. BLIXT.
